United States Patent Office.

JAMES E. TIBBETTS, OF TRENTON, NEW JERSEY.

Letters Patent No. 93,770, dated August 17, 1869.

IMPROVEMENT IN TRUSSES FOR CONNECTING BOOMS TO MASTS.

The Schedule referred to in these Letters Patent and making part of the same.

To all whom it may concern:

Be it known that I, JAMES E. TIBBETTS, of Trenton, in the county of Mercer, and State of New Jersey, have invented a new and improved Truss for Connecting Booms to Masts; and I do hereby declare that the following is a full, clear, and exact description thereof, which will enable others skilled in the art to make and use the same, reference being had to the accompanying drawing, forming part of this specification, in which—

Figure 1 is a side view of my improved device.

Figure 2 is a top view of the same.

Similar letters of reference indicate corresponding parts.

My invention has for its object to furnish an improved device for connecting booms to the masts of vessels, which shall be simple in construction and safe in operation, and which will allow the boom to be conveniently removed when desired; and

It consists in the construction and combination of the various parts of the device, as hereinafter more fully described.

A represents the mast, and B, the boom of a vessel.

C is the truss, which is made in two semicircular parts, which are hinged to each other upon one side of the mast, and detachably connected to each other at the other side of the mast by a bolt and nut, as shown in figs. 1 and 2.

Upon the middle of the part that passes around the rear side of the mast is formed an eye to receive the bolt D, which passes down through said eye, and is secured in place by a nut, d¹, screwed upon its lower end. The nut d¹ is kept from being worked off by

the movement of the boom, by a spring-key passed through a hole in the end of the bolt D, below the said nut. The bolt D is formed with an L-shaped head, d², and with a circular flange, d³, to rest upon the upper side of the eye in the truss C, as shown in the drawings.

To the opposite sides of the L-part of the head d², of the bolt D, are pivoted the lower ends of the straps E, by a bolt which passes through the said head of the bolt D, and through the lower ends of the said straps E, as shown in the drawings. The straps E pass up along, and are securely bolted to the sides of the lower end of the boom B.

The boom B is thus connected with the mast A by a double-jointed connection, giving perfect freedom to the said boom to move in any necessary direction.

A clevis may, if desired, be attached to the head of the bolt D, for convenience in attaching the inner corner of the sail.

Having thus described my invention,

What I claim as new, and desire to secure by Letters Patent, is—

The improved device for connecting the mast-truss and boom-straps of a ship, formed by the combination of the shank of the bolt D, with an L-shaped head, d², circular flange d³, nut d¹, and spring-key, all constructed and co-operating together, as and for the purpose specified.

JAMES E. TIBBETTS.
